ATTORNEY

UNITED STATES PATENT OFFICE.

JOHN F. MAKOWSKI, OF STOCKTON, CALIFORNIA, ASSIGNOR TO CALIFORNIA CEDAR PRODUCTS COMPANY, OF STOCKTON, CALIFORNIA.

PLASTER LATH.

Application filed May 31, 1923. Serial No. 642,498.

To all whom it may concern:

Be it known that I, JOHN F. MAKOWSKI, a citizen of the United States, residing at Stockton, county of San Joaquin, State of California, have invented certain new and useful Improvements in Plaster Lath; and I do declare the following to be a full, clear, and exact description of the same, reference being had to the accompanying drawings, 10 and to the characters of reference marked thereon, which form a part of this application.

This invention relates to the building art and particularly to wall construction.

15 The present invention is designed to produce a strong, fire resisting and water proof lath for supporting plaster, cement or other plastic wall finishes and one which will be particularly adaptable for exterior use when 20 a stucco finish or the like is desired.

The object of the invention is to produce an inexpensive lath which nevertheless will have the same or greater utility than those now produced.

25 The scope and advantages of the invention will readily appear by a perusal of the following specification and claim.

In the drawings similar characters of reference indicate corresponding parts in the 30 several views;

Fig. 1 is a fragmentary perspective view of one of my improved laths.

Fig. 2 is a cross section of an exterior portion of a wall constructed with my improved 35 lath.

Referring now more particularly to the characters of reference on the drawings, the numeral 1 designates a wooden board of any desired length and width, preferably 40 $5\frac{1}{8}'' \times 2'' \times 4''$.

One pair of vertically aligned edges of this board are provided with longitudinal dove tail grooves 2, the front edges of which stop short of the plane of the back or inner edges, 45 or in other words are closer together than said back edges, so that when two boards are set on the wall edge to edge there will be an open space 3 leading into the adjacent dove tail grooves so that plastic material may flow 50 into the same, whereupon such grooves act as a key to further the function of the lath as hereinafter set forth.

In making up my plaster lath I prepare a composition mixture 4 of one part magnesite to one and one half parts filling material 55 such as fuller's earth or other diatomaceous earth and to this I add a solution of magnesium chloride of from 18 to 20% strength to make the composition of a consistency which will readily spread over the front face of the 60 board and into the grooves 2, as shown. This may be applied to the surface of the board in any suitable manner.

While the magnesite composition is still soft I spread on the same, by suitable means, 65 a quantity of small gravel or other suitable objects 5, the same having irregular contours and surfaces. When the magnesite sets this gravel will be firmly and inseparably embedded therein, as the magnesite composition 70 is a binder and adhesive.

The boards are treated as above before being applied to the studding, to which they are secured in close vertical alinement. The 75 spaces or interstices back of and between the gravel particles form a mechanical key or lock for the plaster, cement or other plastic material 6, which is then spread over the same. The gravel being a natural bond for lime, cement or the like, I have found that a 80 very thin layer of the plastic may be spread over the same and at once set up into stucco or other finish and will hold firmly and with no likelihood of cracking, checking or falling off. The dove tail grooves 2 also aid 85 materially in keying the plastic material to the wall, especially since the magnesite and gravel composition surface is followed around into such grooves.

The magnesite, being naturally impervious 90 to moisture and a fire resistant, a wall constructed as shown and described will be of great value to the building industry.

To compensate for any possible warping of the boards and to tend to prevent them 95 from moving apart at their edges with natural contraction, I provide rear longitudinal grooves 7 in the boards, suitably spaced apart.

Having thus described my invention what 100 I claim as new and useful and desire to secure by Letters Patent is:

In a plaster lath comprising a board having grooves formed in parallel edges thereof

and disposed so that when like boards are laid edge to edge, a longitudinal opening will be formed leading to said grooves from one face of the boards to receive plastic material; water proofing material applied in the grooves and to the entire surfaces of the boards to which the plastic material is to be

applied, and mechanical bonding material for said plastic disposed over the surface of the boards and grooves over, and held by, the water proofing material. ¹⁰

In testimony whereof I affix my signature.

JOHN F. MAKOWSKI.
